(57) **CLAIM**

The ornamental design for a pickleball paddle, as shown and described.

DESCRIPTION

FIG. 1 is a perspective view of a pickleball paddle showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top planview thereof;

FIG. 8 is a bottom plan view thereof;

FIG. 9 is a partial enlarged view taken on circle 9 of FIG. 1;

FIG. 10 is a partial enlarged view taken on circle 10 of FIG. 1; and,

FIG. 11 is a partial enlarged view taken on circle 11 of FIG. 2.

The broken lines depict portions of the pickleball paddle that form no part of the claimed design.

1 Claim, 11 Drawing Sheets
